CIRCUIT BREAKER

William W. Camp, Lawrence Township, Mercer County, N.J., assignor to Heinemann Electric Company, Trenton, N.J., a corporation of New Jersey

Filed Mar. 31, 1965, Ser. No. 84,531

Term of patent 14 years

(Cl. D26—13)

FIG. 1 is a back perspective of a circuit breaker, showing my new design;

FIG. 2 is a side elevational view thereof;

FIG. 3 is a back elevational view thereof; and

The essential features of my design are shown in full lines in the drawings.

I claim:

The ornamental design for a circuit breaker, as shown and described.
